UNITED STATES PATENT OFFICE.

CHARLES WELLER, OF NEWARK, NEW JERSEY.

DESIGN FOR A MUSTACHE-GUARD.

SPECIFICATION forming part of Design No. 26,483, dated January 5, 1897.

Application filed November 13, 1896. Serial No. 612,028. Term of patent 7 years.

To all whom it may concern:

Be it known that I, CHARLES WELLER, a citizen of the United States, residing at Newark, in the county of Essex and State of New Jersey, have invented and produced a new and original Design for a Mustache-Guard, of which the following is a specification, reference being had to the accompanying drawings, forming a part thereof, in which—

Figure 1 is a perspective view of a mustache-guard embodying the features of my design, and Fig. 2 is a transverse central section taken on the line 2 2 of Fig. 1.

The design consists in the approximately oval-shaped body A of the guard, having its opposing side edges transversely curved in an outwardly direction. At the center and at each side of the center of the body the trans-

verse shape is that of a compound curve, as shown in Fig. 2, but at the end of the body the transverse section is in the form of a simple curve. The upper face of the body presents a rear convexed surface a, extending from end to end, and a central dished surface a', the edges whereof are provided with scallops a². A hook B is located at each end of the body, and these hooks extend upwardly from the body and slightly over its upper face.

I claim—

The design for the mustache-guard herein shown and described.

CHARLES WELLER.
